UNITED STATES PATENT OFFICE

2,595,777

DEVICE FOR FACILITATING THE BALANCING AND TESTING THE BALANCE OF GRINDING WHEELS

John F. Driver, Fort Wayne, Ind.

Application January 5, 1949, Serial No. 69,304

13 Claims. (Cl. 73—66)

1 The present invention relates to new and useful improvements in grinding wheel supports designed for use in testing the balance of heavy grinding wheels on large industrial grinders.

An important object of the invention is to provide a grinding wheel support by means of which a grinding wheel may be properly balanced without removing the wheel from the grinding machine.

More specifically the invention comprises a removable shaft extension for the grinding wheel of the machine and onto which the grinding wheel is moved into its balance testing position, thereby eliminating any possibility of the wheel slipping or dropping from the hands of the workman during the balancing operation and eliminating the possibility of breakage and damage to the wheel or machine or injury to the person handling the same.

Another object of the invention is to provide a device of this character which can be attached to or removed from the grinding machine without necessitating any changes or alterations in the construction thereof to easily and quickly balance the grinding wheel and eliminating the necessity of the use of hoisting or other equipment for the purpose of completely removing and transporting the heavy wheel to a separate balancing machine and thereby eliminating the need of a separate balancing machine for balancing the wheel.

A still further object is to provide a device of this character of simple construction, which is efficient and reliable in operation, relatively inexpensive to manufacture and otherwise well adapted for the purposes for which the same is intended.

Other objects and advantages reside in the details of construction and operation as more fully hereininafter described and claimed, reference being had to the accompanying drawings forming part hereof, wherein like numerals refer to like parts throughout, and in which:

Figure 1 is a fragmentary side elevational view of a grinding machine showing the grinding wheel in working position thereon and with the balancing attachment shown attached to the shaft of the machine.

Figure 2 is a similar view with parts broken away and shown in section and showing the grinding wheel moved outwardly onto the balancing attachment.

Figure 3 is a view in elevation of the grinding wheel looking toward the outer end of the balancing attachment.

Figure 4 is an enlarged fragmentary sectional

2 view taken substantially on a line 4—4 of Figure 3.

Figure 5 is a transverse sectional view of the balancing attachment taken on a line 5—5 of Figure 4 and

Figure 6 is a perspective view of one of the sectional inserts or sleeves carried by the balancing attachment for the grinding wheel.

Referring now to the drawings in detail where-in for the purpose of illustration I have disclosed a preferred embodiment of the invention, the numeral 5 designates a stud shaft which is internally threaded at its inner end for attaching to the threaded stem 6 at the end of the shaft 7 of a grinding machine 8.

The shaft 5 is formed with a reduced outer end 9 terminating in a hexagonal wrench engaging head or extremity 10 and threaded inwardly thereof as shown at 11.

10 A tubular roller or sleeve 14 is rotatably supported on inner and outer bearing assemblies 12 and 12a at the reduced end portion 9 of shaft 5 by means of an inner retaining ring 13 threaded on reduced end 9 and an outer retaining ring 13a threaded internally in the outer end of roller or sleeve 14.

20 A collar 16 is slidably held on the outer portion of roller 14 by a nut 17 threaded on the outer end of the roller, the collar having a reduced inner end forming a step or shoulder 18.

25 The inner end of roller 14 is also formed with a shoulder 19 and a sectional insert or sleeve 20 is held on the roller 14 between the collar 16 and shoulder 19, the sections of the insert or sleeve 20 having tapered outer surfaces as shown at 21.

30 In the operation of the device, with the shaft extension 5 secured to the shaft 7 as shown in Figure 4 of the drawings, the sectional insert or sleeve 20 is removed and the collar 16 moved inwardly along the roller 14 against shoulder 19.

35 The grinding wheel 22 is then released from shaft 7 and moved outwardly onto the reduced inner end of collar 16 to abut shoulder 18 thereof and the collar 16 and wheel 22 moved outwardly along roller 14 sufficiently to enable the sections of insert or sleeve 20 to be inserted in the hub of the wheel between collar 16 and shoulder 19. Nut 17 is backed outwardly on roller 14 for this purpose. The nut 17 is then tightened to wedge the hub of wheel 22 on the tapered insert or sleeve 20 and the wheel is thus firmly held on the reduced end 9 of stud or shaft extension 5.

45 The wheel may then be freely turned on reduced end 9 of shaft extension 5 to properly test the balance of the wheel and without removing the wheel from the grinding machine.

In view of the foregoing description taken in conjunction with the accompanying drawings it is believed that a clear understanding of the device will be quite apparent to those skilled in this art. A more detailed description is accordingly deemed unnecessary.

Having described the invention, what is claimed as new is:

1. The combination with a grinding machine shaft, of a stud shaft removably carried at the end of the first named shaft and onto which a grinding wheel is axially movable from its position on the first named shaft, said stud shaft including relatively stationary and revolute parts on the latter of which the grinding wheel is rotatably supported.

2. The combination with a grinding machine shaft, of a stud shaft removably carried at the end of the first named shaft and onto which a grinding wheel is axially movable from its position on the first named shaft, said stud shaft including relatively stationary and revolute parts on the latter of which the grinding wheel is rotatably supported and means carried by the stud shaft for locking the wheel on said revolute part.

3. The combination with a grinding machine shaft, of a stud shaft on the end of said first named shaft, a carrier slidable on the stud shaft supporting a grinding wheel for sliding the wheel from its position on the first named shaft onto the stud shaft for free rotation thereon, and means locking the wheel on the stud shaft.

4. The combination with a grinding machine shaft, of a wheel balance tester comprising a stud shaft on the end of the first named shaft, a collar slidable on the stud shaft and supporting a grinding wheel for moving the wheel from its position on the first named shaft onto the stud shaft for free rotation thereon, and means locking the wheel on the stud shaft.

5. The combination with a grinding machine shaft, of a wheel balance tester comprising a stud shaft on the end of the first named shaft, a stepped collar slidable on the stud shaft and supporting a grinding wheel on one of its steps for moving the wheel from its position on the first named shaft onto the stud shaft for free rotation thereon, and means carried by the stud shaft locking the wheel thereon against the collar.

6. The combination with a grinding machine shaft, of a wheel balance tester comprising a stud shaft on the end of the first named shaft, a stepped collar slidable on the stud shaft and supporting a grinding wheel on one of its steps for moving the wheel from its position on the first named shaft onto the stud shaft for free rotation thereon, and means carried by the stud shaft locking the wheel thereon against the collar, said means comprising a sectional tapered sleeve removably positioned in the hub of the wheel and removably secured on the stud shaft.

7. The combination with a grinding machine shaft, of a wheel balance tester comprising a stud shaft on the end of the first named shaft, a stepped collar slidable on the stud shaft and supporting a grinding wheel on one of its steps for moving the wheel from its position on the first named shaft onto the stud shaft for free rotation thereon, and means carried by the stud shaft locking the wheel thereon against the collar, said means comprising a sectional tapered sleeve removably positioned in the hub of the wheel and locked on the stud shaft by said collar.

8. The combination with a grinding machine shaft, of a wheel balance tester comprising a

stud shaft on the end of the first named shaft, a hollow roller journaled on the stud shaft concentrically therewith, a stepped collar slidable on the roller and supporting a grinding wheel on one of its steps for moving the wheel from its position on the first named shaft onto the roller, and means for locking the collar and wheel on the roller.

9. The combination with a grinding machine shaft, of a wheel balance tester comprising a stud shaft on the end of the first named shaft, a hollow roller journaled on the stud shaft concentrically therewith, a stepped collar slidable on the roller and supporting a grinding wheel on one of its steps for moving the wheel from its position on the first named shaft onto the roller, and means for locking the collar and wheel on the roller, and including a tapered sectional sleeve removably carried by the roller and wedged in the hub of the wheel.

10. The combination with a grinding machine shaft, of a wheel balance tester comprising a stud shaft on the end of the first named shaft, a hollow roller journaled on the stud shaft concentrically therewith, a stepped collar slidable on the roller and supporting a grinding wheel on one of its steps for moving the wheel from its position on the first named shaft onto the roller, and means for locking the collar and wheel on the roller, and including a tapered sectional sleeve removably carried by the roller and wedged in the hub of the wheel, and held against a part of the roller by the collar.

11. A grinding wheel balance testing attachment for grinding machines comprising a shaft extension including an inner relatively stationary part and an outer revolute part, and means connecting the shaft extension to the spindle of the grinding machine in a position for transferring a grinding wheel from the spindle onto the revolute part of the shaft extension for free rotation of the wheel thereon.

12. A grinding wheel balance testing attachment for grinding machines comprising a shaft extension including an inner relatively stationary part and an outer revolute part, means connecting the shaft extension to the spindle of the grinding machine, and transfer means on the shaft extension for moving a grinding wheel from the spindle onto the revolute part of the shaft extension for free rotation of the wheel thereon.

13. A grinding wheel balance testing attachment for grinding machines comprising a shaft extension, means connecting the shaft extension to the spindle of the grinding machine, a roller journaled on the shaft extension concentrically therewith, a collar slidably carried by the roller and supporting a grinding wheel for transferring the wheel from the spindle onto the roller, and means carried by the roller locking the wheel thereon.
